UNITED STATES PATENT OFFICE

DAVID FRANK GLEDHILL, OF UPPER MONTCLAIR, NEW JERSEY, ASSIGNOR TO PENN-SYLVANIA TEXTILE MILLS, INC., OF CLIFTON, NEW JERSEY, A CORPORATION OF NEW JERSEY

DESIGN FOR A TEXTILE FABRIC

Application filed November 3, 1930. Serial No. 37,513. Term of patent 3½ years.

To all whom it may concern:

Be it known that I, DAVID FRANK GLEDHILL, a citizen of the United States, and a resident of Upper Montclair, county of Essex, State of New Jersey, whose post-office address is No. 295 Fifth Avenue, city of New York, county of New York, and State of New York, have invented a new, original, and ornamental Design for a Textile Fabric, of which the following is a specification, reference being had to the accompanying drawing, forming part thereof.

The figure is a plan view of a textile fabric showing my new design. A single unit of my design is substantially comprised within the area defined by the indicating lines shown on the drawing. This unit is repeated over the surface of the fabric in the relation indicated by dotted lines.

I claim:

The ornamental design for a textile fabric substantially as shown and described.

DAVID FRANK GLEDHILL.
